COMBINATION COUNTERTOP AND SINK

Robert W. Fink, Benton Harbor, Mich., assignor to Whirlpool Corporation, a corporation of Delaware

Filed Sept. 23, 1965, Ser. No. 87,137

Term of patent 14 years

(Cl. D4—2)

Fig. 1

Fig. 3

Fig. 4

Fig. 2

Fig. 5

Fig. 6

The dominant features of my design are shown in full lines.

I claim:

The ornamental design for a combination countertop and sink, as shown and described.
